UNITED STATES PATENT OFFICE.

ROBERT BREWSTER, OF CHICAGO, ILLINOIS.

SPARK-PLUG.

1,294,229.

Specification of Letters Patent. Patented Feb. 11, 1919.

Application filed January 14, 1910. Serial No. 211,729.

To all whom it may concern:

Be it known that I, Robert Brewster, subject of the King of Great Britain, residing at Chicago, in the county of Cook and State of Illinois, have invented certain new and useful Improvements in Spark Plugs, of which the following is a specification.

My invention relates to improvements in spark plugs.

One of the objects of my invention is to provide a spark plug which will produce a larger and more enduring flame than heretofore has been accomplished, without materially increasing the power or electro-motive force of the source of current supply.

Other and further objects of my invention will become readily apparent to persons skilled in the art, from a consideration of the following description when taken in conjunction with the accompanying drawings, wherein—

Figure 1 is an elevation of the plug showing part in central section.

Fig. 2 is an end view of the bottom end of the plug.

In both views the same references are used to indicate similar parts.

My improved plug is intended to be used for igniting the fuel charges in internal combustion engines.

Theoretically, the power charge of an internal combustion engine should be ignited, after being compressed, immediately at the beginning of the power stroke. Practically, however, this act would be too late for efficiency in the cyclic operation of the piston, owing to the lapsed time interval between the initial ignition and the complete combustion of the charge. There is an appreciable lapse of time, owing to the lag effected by flame propagation, within which combustion will be completed. Therefore, in the practical operation of an engine of this type, the spark is usually made ahead of this theoretical ignition point to compensate for this delay. If the duration of the spark-time could be made coextensive with the combustion interval, then the lag between initial ignition and completed combustion could be shortened and a nearer approach to theoretical conditions would be effected with attendant increase of economy.

Velocity of flame propagation is enhanced, if a spark is maintained in the charge

during the entire time when combustion is in progress. I therefore, provide a spark plug having a plurality of spark gaps between adjacent ball terminals. My plug is based upon the operation of the well known static generators or Toepler-Holtz machines. In these machines if the two ball terminals be replaced with point or angular terminals, there will be a continuous ineffective silent brush discharge, visible more clear in a dark room. If these points be replaced by balls, the machine being rotated at a constant speed, there will be a series of violent disruptive discharges between the balls, separated by appreciable time intervals. When the balls are used the charge accumulates on them, and is bound, until its electro-motive force is sufficient to overcome or break down the intervening air resistance.

In my spark plug there are a number of balls between the main terminal balls. The charge must accumulate on these balls, respectively, before the "spark" or the disruptive discharge takes place between adjacent balls. The spark, therefore, is made in consecutive sequence between adjacent balls and as there is an appreciable time interval between each disruptive discharge, the total time may be made to coincide with the time required for flame propagation by proportioning the number of intervening spark gaps and the distance of separation of the balls.

The first spark will initially ignite the charge and the subsequently occurring sparks will serve to maintain ignition, by this means, until combustion has been entirely completed.

In the drawings 5 is an externally threaded casing within which is secured an insulation core 6 of porcelain or the like. A central conductor 7 terminates in the wire binding terminal 8, at the top of the structure, and terminates in the ball 9, one of the main terminals at the bottom of the structure. Another main terminal 10 having a ball 11 surmounted on its free end is secured in the lower edge of the casing 5, as at 12. A series of spaced-apart intervening balls, 13 to 19 inclusive, mounted on stems 105 that are embedded in the insulator 6, preferably when the latter is in a plastic state, provides seven spark gaps. 6' is a partition wall to prevent short circuiting of the contacts of the plug.

The use and operation of a spark plug is too well known and understood to require specific elucidation here.

It is assumed that the spark will occur 5 progressively between the successive pair of balls in the circle of terminals or electrodes.

While I have herein shown a single embodiment of my invention it is manifest 10 that various changes and disposition of parts may be made within the scope of the appended claims.

Having described my invention, what I claim is:

15 1. A spark plug comprising a shell and an inclosed insulating core; a centrally disposed electrical terminal projecting from one end of the core; a parti-circular insulating wall projecting from the core partly 20 surrounding said terminal; a terminal se-

cured to the lower edge of the shell and a series of spaced-apart electrically-conducting bodies between said terminals outside of said wall.

2. A spark plug comprising a shell and 25 a core; a centrally disposed, globular, electrical terminal projecting from the inner end of the core; a similar terminal secured to the inner end of the shell; a series of globular electrodes, supported on the core 30 and arranged in spaced-apart circular sequence around the central terminal, and a part-circular wall, of insulating material, between the central terminal and said electrodes.

In testimony whereof I hereunto set my hand in the presence of two subscribing 35 witnesses.

ROBERT BREWSTER.
